UNITED STATES PATENT OFFICE.

GEORGE J. GENUNG, OF BEAVER FALLS, AND WILBERT L. WELSH, OF NEW BRIGHTON, PENNSYLVANIA.

SAND TOY.

1,417,512.

Specification of Letters Patent. Patented May 30, 1922.

Application filed January 29, 1921. Serial No. 441,060.

To all whom it may concern:

Be it known that we, GEORGE J. GENUNG and WILBERT L. WELSH, citizens of the United States, residing at Beaver Falls and 5 New Brighton, respectively, in the county of Beaver, State of Pennsylvania, have invented a new and useful Sand Toy, of which the following is a specification.

This invention relates to figured toys, and 10 more particularly to toys of this character wherein the figures are caused to move simulating movements of a human being.

The primary object of the invention is to provide a toy of this character wherein the 15 figures are moved by a novel mechanism, eliminating all spring and perishable structures in the operation of the device.

A further object of the invention is the provision of gutters or the like for directing 20 sand to the propelling wheel, forming a part of the operating mechanism, whereby the weight of the sand causes the wheel to revolve.

With the foregoing and other objects in 25 view which will appear as the description proceeds, the invention resides in the combination and arrangement of parts and in the details of construction hereinafter described and claimed, it being understood that 30 changes in the precise embodiment of the invention herein disclosed, may be made within the scope of what is claimed, without departing from the spirit of the invention.

Referring to the drawings:—

35 Figure 1 illustrates a front elevational view of a toy constructed in accordance with the present invention.

Figure 2 illustrates a front elevational view of the operating mechanism, the cover 40 of the toy being removed, and portions of the mechanism being broken away.

Figure 3 illustrates a sectional view taken on line 3—3 of Figure 1.

Figure 4 illustrates a fragmental sectional 45 view taken on line 4—4 of Figure 3.

Figure 5 illustrates a detail view of the propelling wheel, one of the side plates thereof being removed.

Referring to the drawings in detail, the 50 toy includes a box-like casing which is formed with a rear wall 5 and a front wall 6, the walls being spaced apart to provide a compartment for the operating mechanism.

The front wall 6 is also spaced from the 55 front edges of the side and end walls 7 of

the casing to provide a compartment 8 at the front of the casing, the latter compartment being designed to accommodate the figures, forming a part of the toy, and which in the present showing are indicated by the reference character 9.

Each of these figures includes a movable body portion 10 which is pivotally connected to the leg portions 11 of the figure as by means of the curved arms 12, there being provided an enlargement 13 on each of the arms for connecting the arms to the body portions 10 so that the body portions 10 will move with the arms.

Each of these arms 10 extends downwardly and has connection with an operating rod 14 as at 15, the intermediate portion of the rod being formed into a pair of loops 15 which receive the lower extremities of the spaced arms 16, the upper portions of the 75 arms being pivotally connected to the front wall by means of the pivot 17. Thus it will be seen that the arms 16 are free to oscillate, which oscillation results in a relative movement of the rod 14 to accomplish the movement of the body portions of the figures.

A supporting bracket 18 has its ends secured to the front wall 6 as by means of the screws 19, the bracket 18 having a portion thereof disposed in spaced relation with the front wall 6 of the casing to permit the propelling wheel 20 to be positioned therebetween. This propelling wheel comprises side plates 21 and angular plates 22 forming pockets, and as shown, a central shaft 23 90 supports the propelling wheel within the bracket member.

Carried by the propelling wheel 20 and mounted eccentrically thereon, is a laterally extending operating pin 24 that moves between the arms 16, contacting with the arms to move the same laterally and simultaneously moving the rod 14, which in turn operates the figured members.

A sand gutter indicated at 25 is positioned 100 within the casing and has its side edges closely engaging the front and rear walls thereof, to eliminate any possibility of the sand, or operating medium passing between the side edges of the gutter and the walls 105 of the casing, thereby insuring the entire quantity of sand passing to the pockets 22.

This gutter 25 also has its upper end closely engaging one wall of the casing, while the opposite end thereof is disposed 110

in spaced relation with the casing, and has its lower extremity curved inwardly as at 26 to guard against the sand passing to the wheel, on the movement of the sand to the 5 trough 27.

The trough 27 is provided with an outlet opening 28 which opening is disposed directly above the path of travel of the pockets 22 so that the discharge of sand through the 10 opening will be directed to the pockets.

In the operation of the device, the casing is tilted to cause the sand to move within the trough 27, whereupon the casing is moved to an upright position with the result that the sand gravitates through the opening 28 and falls into one of the pockets of the propelling wheel. When the weight of the sand within the pocket is sufficient to overbalance the wheel, the wheel is moved, 20 causing the pin 24 to oscillate the arms 16 which in turn impart reciprocatory movement to the rod 14 and arms 12, with the result that the body portions 10 move to simulate persons hammering. It is of course understood that as the propelling wheel moves, the sand is deposited in the lower 25 side of the casing.

Having thus described the invention, what is claimed as new is:—

30 1. In a toy, a casing including front and rear walls, pivoted members supported by the front wall, a propelling wheel, a member including a pair of arms pivotally connected to the propelling wheel, a pin extending from the propelling wheel and adapted to contact with the arms, curved arms having connection with the pivoted members, a rod connecting the curved arms to move the same, a gutter disposed between 35 the front and rear walls, said gutter having 40

an opening to permit the passage of sand therefrom, said opening adapted to direct sand to the propelling wheel for rotating the same, and a bracket for supporting the propelling wheel.

45

2. In a toy, a casing including front and rear walls, pivoted members connected to the front wall, a propelling wheel pivotally supported by the front wall, curved arms having connection with the pivoted members, a rod connecting the curved arms, spaced arms pivotally supported by the front wall, means carried by the propelling wheel and contacting with the spaced arms for moving the arms, means for connecting the spaced arms and rod, and means for directing sand to the propelling wheel for operating the same.

50

3. In a toy, a casing including front and rear walls, a bracket member supported by the front wall, a propelling wheel supported by the bracket, a gutter supported by the front wall, said gutter including a trough, said trough having an opening, pivoted members supported adjacent to the front wall, pivoted arms for supporting the pivoted members, a rod having connection with the arms, and means carried by the propelling wheel and contacting with the pivoted arms for causing the operation of the pivoted members.

55

In testimony that we claim the foregoing as our own, we have hereto affixed our signatures in the presence of two witnesses.

GEORGE J. GENUNG.
WILBERT L. WELSH.
